E. O. RANDALL

TAG

Filed Sept. 12, 1927

UNITED STATES PATENT OFFICE.

EDWARD O. RANDALL, OF BALTIMORE, MARYLAND.

TAG.

Application filed September 12, 1927. Serial No. 219,139.

My invention relates to improvements in tags and more particularly to advertising tags adapted to be secured to the license plates of automobiles.

5 It is a general object of my invention to provide a novel and improved tag.

More particularly it is an object of my invention to provide an advertising tag made of tin, celluloid, or some other thin pliable 10 material which may be quickly and easily attached to an automobile license plate.

A further object of my invention is to provide an advertising tag which may be attached to the license plate of an automobile 15 without the use of tools, and which will not obscure any of the information displayed on the license plate.

A still further object is to provide a tag which may have any sort of advertising or 20 information printed, stamped or embossed thereon, and which will be attractive in appearance, and cheap to manufacture.

With these and other objects in view, the invention contains certain novel features 25 which will be more fully described and set forth in the appended claims.

In the accompanying drawings forming part of this application,

Figure 1 is an elevational view showing 30 my improved tag mounted on a license plate.

Figure 2 is a section on the line 2—2 of Figure 1.

Figure 3 is an elevation of my improved tag.

35 Figure 4 is a cross section on the line 4—4 of Fig. 3.

Figure 5 is an elevation of a modified form of tag.

Figure 6 is an elevation of a still further 40 modified form of tag mounted on a license plate, and

Figure 7 is a section on the line 7—7 of Figure 6.

My improved tag may be made of tin, cel- 45 luloid, or some other thin pliable material, which may readily be bent with the fingers, yet is sufficiently rigid to retain its shape once it is placed in position.

Referring to Figs. 1—4, it will be seen that 50 the tag comprises a body portion 10, preferably of some metal such as tin, which may be of any desired shape and from which is struck up a lug 11. This lug is preferably located midway of the side edges

55 12 and 13 of the portion 10, and its lower edge is an appreciable distance above the

points 14 and 15, which may be said to be the lower corners of the body portion. The lug 11 is bent outwardly from the body portion, a distance equal to the thickness of a 60 license plate, and when the tag is placed in position on the upper edge of the license plate as shown in Fig. 1, the lug 11 will be in front of the license plate and part of the body portion behind the same. In this manner the tag is mounted in position on the license plate, and as the lug projects below the upper edge of the plate but a short distance and is relatively narrow, none of the 65 information on the plate is obscured. 70

The greater part of the body portion 10 projects above the upper edge of the license plate, as clearly shown in Fig. 1, and on this portion may be printed, stamped, or embossed advertising matter or any information 75 desirable.

To secure the tag firmly to the license plate so that it will not become displaced, a tongue 16, preferably integral, is formed on the lower part of the portion 10. This tongue is 80 defined by the edges 17 and 18 which start at the points 14 and 15 and preferably curve inwardly and downwardly merging into the substantially parallel edges 19 and 20. The lower end of the tongue 16 is adapted to be 85 bent around the lower edge of the license plate, and in cooperation with the lug 11 to securely hold the tag on the license plate. The tongue 16 at its lower end is relatively 90 narrow and the bent over portion will not obscure any information on the plate. A reinforcing rib 21 may be formed on the tongue 16, as shown in Fig. 4, if desired, to strengthen the same. 95

It will be seen, therefore, that to secure a tag to a license plate, it is simply necessary to place the tag with the lug 11 projecting over the upper edge of the plate and to bend the lower end of the tongue 16 around the lower edge of the plate, the greater part of the body portion of the tag projecting above the license plate. In this manner the tag is securely held to the plate without danger of coming loose, no tools are required, and it only takes a moment to carry out the operation. At the same time a neat and attractive advertising tag is displayed without in any way obscuring any information on the license plate. 100 105

In Figure 5, I show a slight modification 110 in which two lugs 22 are formed on the body portion. These lugs are preferably made by

cutting inwardly from the side edges 12 and 13 and slightly upwardly. The lugs are then bent outwardly from the body portion, a distance equal to the thickness of a license plate. 5 With this form, the tongue 16 is the same as described in connection with Figs. 1 to 4.

In Figs. 6 and 7, I show a still further modification in which the tag is preferably made of celluloid or some similar material. 10 In this case, it is possible that the lower end of the tongue 16 would not stay bent around the lower edge of the license plate, and so to insure against the tag becoming loose I provide a U-shaped clip 23 which is slipped over 15 the lower end of the tongue after it is bent around the license plate to hold it in position. Also, I provide two lugs 24 formed similar to the lug 11 in Figs. 1-3.

By making a tongue which is bent around 20 the lower edge of a license plate, without any special fastening means, I am able to provide a tag which will fit any license plate, although they often vary somewhat in width in the different States.

25 While I have shown two lugs in each of the forms shown in Figs. 5 and 6, I do not limit myself to this number, but may provide more if so desired, or only one lug, such as shown in the preferred form. Also, other 30 slight changes may be made without departing from the spirit of the invention, and hence I do not consider myself bound by the precise details set forth, but only by the scope of the appended claims.

35 I claim:—

1. A tag comprising a body portion, a lug thereon adapted to fit over one edge of a support, a tongue secured to the body portion

and adapted to be bent around the opposite edge of the support, and a clip holding said bent portion in position. 40

2. A tag adapted to be supported on a license plate including in combination, a body part of thin material, a lug struck up from said body part and adapted to engage over 45 one edge of said plate with a portion of said body part behind said plate, and a portion extending freely beyond said plate, a tongue extending from the portion of said body part behind said plate and adapted to be bent over 50 the opposite edge of said plate.

3. A tag adapted to be supported on a license plate and formed from a sheet of thin material into a body part and a tongue extending from one edge thereof, a lug on the tag adapted to engage over one edge of said plate with said body part extending freely 55 beyond said plate and with said tongue extending behind said plate, said tongue having an end adapted to be bent around the opposite edge of said plate to retain the tag in position. 60

4. A tag adapted to be supported on a license plate and formed from a sheet of thin material into a body part and a tongue extending from one edge thereof, a lug struck up from said material near the edge from which said tongue extends and adapted to engage over one edge of said plate and to extend partly over the front face thereof, said body part extending freely beyond said plate 65 and substantially in the plane thereof, said tongue adapted to extend behind said plate 70 and to have its end bent around the opposite edge thereof.

In testimony whereof I affix my signature.
EDWARD O. RANDALL.
